(57) **CLAIM**

The ornamental design for wall hanging article keeper, as shown and described.

DESCRIPTION

FIG. 1 is a front view of wall hanging article keeper embodying my new design;

FIG. 2 is a left side view thereof;

FIG. 3 is a rear view thereof;

FIG. 4 is a plan view thereof;

FIG. 5 is a bottom view thereof;

FIG. 6 is an environmental perspective view thereof; and,

FIG. 7 is a reduced scale environmental perspective view.

The broken line showing of partial structure and a hook is included for the purpose of illustrating environment and forms no part of the claimed design.
